(57) **CLAIM**

The ornamental design for a work glove as shown and described.

DESCRIPTION

FIG. 1 is a perspective view of the work glove in accordance with the present invention;

FIG. 2 is a plan view of the work glove of FIG. 1;

FIG. 3 is a first side view of the work glove of FIG. 2;

FIG. 4 is a second opposite side view of the work glove of FIG. 2;

FIG. 5 is a first end view of the work glove of FIG. 2; and, FIG. 6 is a second opposite end view of the work glove of FIG. 2.

The broken lines illustrate portions of the work glove that form no part of the claimed design.
